UNITED STATES PATENT OFFICE.

ARTHUR P. STRONG, OF CHICAGO, ILLINOIS, ASSIGNOR TO GREEN ENGINEERING COMPANY, OF EAST CHICAGO, INDIANA, A CORPORATION OF ILLINOIS.

ASH-CONVEYING SYSTEM.

1,301,194.

Specification of Letters Patent. Patented Apr. 22, 1919.

Application filed April 6, 1917. Serial No. 160,254.

To all whom it may concern:

Be it known that I, ARTHUR P. STRONG, a citizen of the United States, residing at Chicago, in the county of Cook and State 5 of Illinois, have invented new and useful Improvements in Ash-Conveying Systems, of which the following is a specification.

This invention relates to improvements in pneumatic conveying systems for the removal of ashes from steam boiler furnaces, and more particularly to a device adapted for use in connection with certain fittings employed in the system and having removable parts, for the purpose of removing, 15 supporting, and replacing such parts, and to thereby facilitate the convenient inspection, replacement, or other operation thereon.

Conveying systems of the character described ordinarily comprise systems or lines of metal conduits or pipes, installed in convenient proximity to the furnaces and extending to a common point of disposal or tank, usually located exterior of the boiler room. A common arrangement of piping consists in providing a horizontal pipe extending along and in front of the boiler and a short distance above the boiler room floor, said horizontal pipe having a suitable 20 number of intake openings, into which the ashes are emptied. The horizontal pipe communicates with other pipes, ordinarily a vertical riser extending to the ceiling and a horizontal pipe extending to the tank or 25 receptacle. Whatever may be the arrangement of piping in a particular installation, curved or elbow fittings are employed to make connection between pipes arranged at angles to each other, these fittings having 30 the general form of the standard elbow fitting, but having certain modifications in construction, owing to the character of material handled, namely, the provision of removable wearing backs or sections of hard 35 metal, mounted within the fitting and forming the surface of the passage therethrough which is subjected to the abrasive action of the material, the same being manifestly greater at the bends or turns where such fittings are located, owing to the abrupt change 40 in the direction of flow of the material at these points. Although these "wearing backs" protect the fitting from the abrasive action, they nevertheless become worn 45 and must be replaced from time to time

with new ones. For this reason the fittings are constructed so as to permit the removal of the wearing backs by providing a cover or removable section of the fitting which extends over the wearing back and is 60 capable of being removed in order to withdraw the wearing back.

In large installations, the correspondingly large capacity of the system requires the use of pipes, fittings, and parts of considerable size and weight, and for that reason the operation of removing and handling the parts of the fittings is exceedingly difficult of accomplishment by hand, owing to their weight and size, and further 65 because the location of the fittings is often such as to make the fittings difficult of access for conveniently removing the necessary parts of the fitting to replace or inspect the same. 70

The purpose of this invention is, therefore, to provide a construction for a device designed to enable the removable portions of fittings of the kind described, to be easily removed, and further for supporting the 75 same when detached and moving the same bodily away from the main portion of the fitting, thereby permitting the necessary adjustments or replacement to be made under the most favorable conditions. 80

A preferable construction for accomplishing the objects of this invention is herein-after fully described and illustrated in the accompanying drawings, wherein— 85

Figure 1 is a view in side elevation of an 90 elbow fitting and the device in position for supporting and/ removing the removable section therefrom;

Fig. 2 is a view in end elevation of the 95 elbow fitting and the device; and

Fig. 3 is a view in cross-section of the device, taken on line 3—3 of Fig. 1.

As illustrated in the drawings, an elbow fitting 10 connects a horizontal pipe or conduit 11 with a vertical conduit or riser 12, arranged at right-angles to each other, the horizontal conduit being preferably located a short distance above the floor 13 of the boiler room. The elbow fitting 10 resembles, in general appearance, a standard elbow fitting, having a curvilinear central passage and provided at its ends with flanges 14, 14, to which are connected similar flanges 15, 15 of the conduits 11 and 12, said flanges being connected together in the usual manner 110

by means of bolts. The elbow fitting comprises a main section or body 16 and a removable section or cover 17, which forms the portion of the fitting extending between the 5 end flanges 14, 14 and throughout the portion of maximum curvature thereof. The cover or removable section is joined to the main section along the parting line extending at an angle of 45° to the planes of the 10 flanges 14, 14, there being provided on opposite sides of said parting line and integral with the body 16 and cover 17, a series of pairs of lugs 18, through which extend bolts 19, which connect the parts together in the 15 usual manner. In the position shown, the elbow is so arranged that the cover plate 17 extends throughout the under and outer sides of the elbow, so that in removing the same a downward and outward movement 20 would be necessary. The cover plate 17 is a hollow or dish shaped member which supports a wearing back (not shown), said wearing back having a somewhat similar contour to that of the cover and forming the 25 surface of the passage of the fitting through the surface of maximum curvature. The wearing back is preferably seated within the cover plate 17 and fixed thereto by means of suitably arranged set screws 20.

30 Referring now to the construction of the device designed to facilitate the removal of the cover plate and for the purposes hereinbefore set forth, the same comprises, in general, a truck 21 provided with wheels 22 35 movable upon the tracks 23, extending transversely of the horizontal conduit 11 and beneath the elbow, and a horizontally movable supporting frame 24 supported upon the truck 21 in a manner to be moved trans- 40 versely of the direction of movement of the truck 21.

The truck may be of any suitable construction, though preferably comprising parallel side frame members 25, having the form 45 of channel bars, said side frame members being connected at their ends by transverse frame members 26, bolted to the side frame members adjacent their ends. Fixed to the under flanges of the side frame members 25 and adjacent their ends are provided journal bearings 27, 27, each pair of journal bearings supporting an axle 28, upon which are mounted the wheels 22. Upon the upper margins of the side frame members 25, rests 50 the supporting frame 24, the same comprising two vertical side plates or frame members 29, 29, arranged in parallel relation and spaced apart a distance substantially equal to the width of the elbow fitting. The side plates 29, 29 are generally triangular in shape, having the central portions removed to reduce the weight, and connected together at suitable points by means of a number of tie-bars 30, 30. As before suggested, the 55 supporting frame 24 extends transversely of

the truck and rests upon the upper edges of the side frame members 25, 25, each of the side plates 29, 29 having a lower rail 31 slightly greater in length than the width of the truck and bearing at its under surface 70 upon the upper surfaces of the side frame members 25. At either side of the rails 31 of the side plates 29, 29 are provided upright guides 32, having the form of angle-irons extending transversely of the truck frame 75 and secured thereto, the vertical webs of said angle-irons forming between them grooves or guide-ways for the rails 31, 31 of the supporting frame.

At two of the corners of the triangularly 80 shaped side plates, to wit, the upper corner or apex and the lower corner adjacent the elbow, are provided notches 33 and 34, respectively, said notches preferably having a horizontal bearing surface and a vertical surface, the latter facing in the direction of the elbow. Just forwardly of each of the notches 33 and 34 are provided inclined surfaces 35, which slope downwardly from the forward edge of the notches at an angle sufficient to 90 provide a gently inclined approach to the notches. The function of the inclined surfaces 35 will be hereinafter pointed out. These notches are adapted to engage pairs of lugs 36 extending laterally from the cover 95 17 and at right-angles to the plane of the side plates 29, said lugs 36 being preferably cast integral with the cover plate, and located adjacent to the line of parting or bearing edges, one pair of lugs, to wit, the uppermost pair, being located intermediate the ends of the cover and substantially in vertical alignment with the axis of the vertical conduit 12, and the lowermost pair of lugs 36 adjacent the lower end of the cover 17. 105

From the foregoing description it is manifest that the supporting frame is movable inwardly and outwardly toward the cover 17, in order to engage the lugs 36, and, for the purpose of actuating the supporting frame, 110 the following mechanism is preferably employed: Extending transversely of the truck and intermediate the side plates 29, 29 is mounted a screw shaft 37, the same being supported in bearings 38, 38 rigidly fixed to 115 the upper flanges of the side frame members 25, 25, said screw shaft projecting outwardly beyond the outer or rear side of the truck and provided at its end with a crank handle, 39. Integral with the supporting frame 24 120 and extending transversely between the lower rails 31, 31 thereof, is a bar 40, which carries at its central portion a boss or integral nut 41 having a screw-threaded bore, which engages the screw shaft 37. By this mechanism the supporting frame of the truck is capable of being moved upwardly and forwardly by rotating the screw shaft 37, through the medium of the crank 39, in the proper direction. 130

Having described the construction of the device embodying the invention, the purpose and function thereof will be understood from the following: Assuming that it is desired 5 to remove the cover plate 17 of the elbow 10, the truck is first moved along the tracks 23 to a position beneath the elbow, the supporting frame being previously moved outward so that the same will clear the elbow and 10 pass beneath the same. The truck being brought to rest beneath the elbow, the crank will then be rotated in a direction to move the supporting frame forward in its guides until the forward ends of the inclined bearing surfaces 35 will come in contact with 15 the lugs 36, 36. By further rotating the crank the inclined bearing surfaces 35 will pass beneath the lugs 36 and by so doing tend to raise the cover 17, that is, force it 20 tightly against the body 16. Still further movement of the supporting frame carries the notches 33 and 34 into full engagement with the lugs 36, whereupon the supporting frame will be brought to rest, the cover plate 25 being thus securely supported by reason of the engagement of the horizontal bearing surfaces of the notches and lugs. In this position the bolts 19 can be easily removed, thus disconnecting the cover from the body 30 16. Now, by rotating the screw shaft in the opposite direction, the supporting frame with the cover mounted thereon will be drawn backward in a horizontal direction away from the body 16. When the distance 35 of movement is sufficient to entirely clear the body of the fitting, the truck can be moved in either direction along the tracks 23, thereby transporting the cover to either side of the elbow and into a position where the 40 cover plate and the wearing back supported thereon can be operated upon for inspecting the amount of wear suffered by the wearing back, or, if necessary, removing the same and replacing it by a new one. Furthermore, the 45 cover and wearing back being entirely removed from the elbow, the body and adjacent parts of the conduit are clearly exposed for the purpose of inspection.

All the necessary repairs or replacements 50 having been made, the truck is again wheeled back to a position beneath the elbow, and the supporting frame then moved forwardly by rotating the screw shaft 37, thus bringing the cover plate into registering relation with 55 the body 16. When these parts are properly brought into contact the bolts are again inserted and tightened, whereupon the supporting frame is again moved backwardly and clear of the elbow. The operation having 60 been completed, the truck can be wheeled out of the way to a place provided, until again needed, or else transported by a system of tracks to other elbows similarly placed for the purpose of repeating the operation 65 hereinabove described.

It is manifest from the foregoing description of the construction and operation of the device that the same provides an efficient and simple means for removing a cover and wearing back of an elbow fitting, and in such a 70 manner that the same can be easily carried to a position where the necessary operation can be accomplished with the utmost ease and facility, the removed parts being supported in the meantime in the most desirable 75 position for making the necessary alterations, whereupon the parts can be replaced with the same degree of ease. The use of the device herein set forth avoids the necessity of lifting the parts by hand and otherwise exerting physical effort in the manipulation of the parts, thus making it comparatively simple to inspect the fittings at frequent intervals, whereas otherwise it would be neglected on account of the amount of 80 physical labor attending the operation.

I claim as my invention:

1. In a conveying system, the combination of a pipe connecting fitting, comprising a body member having a removable wall section 90 adapted to support a wear section for said fitting, and means independent of said pipe section for supporting said wall section when disconnected from said body member and for moving the same into and 95 out of engagement with said body member.

2. In a conveying system, the combination of a pipe connecting fitting, comprising a body member having a removable wall section 100 adapted to support a wear section for said fitting, and means independent of said pipe fitting for supporting said wall section when disconnected from said body member and for moving the same into and 105 out of engagement with said body member and to one side of the latter.

3. In a conveying system, the combination of a pipe connecting fitting, comprising a body member having a removable wall section 110 adapted to support a wear section for said fitting, a supporting member independent of said pipe fitting and adapted to be moved into and out of engagement with said wall section and upon which the latter rests when disconnected from said body member, and means for supporting said supporting member and for moving the same to one side of said pipe fitting.

4. In a conveying system, the combination of a pipe connecting fitting, comprising a 120 body member having a wall section detachably connected therewith and adapted to support a wear section for said pipe fitting, a supporting frame adapted to be engaged with said wall section and to support the 125 same in registering relation with said body member, and trucks supporting said frame.

5. In a conveying system, the combination of a pipe connecting fitting, comprising a body member having a wall section detach- 130

ably connected therewith and adapted to support a wear section for said pipe fitting, a truck movable beneath said detachable wall section, a supporting frame movably mounted on said truck, and means for actuating said frame into supporting engagement with said detachable wall section.

6. In a conveying system, the combination of a pipe connecting fitting, comprising a body member having a wall section detachably connected therewith and adapted to support a wear section for said pipe fitting, a truck movable beneath said detachable wall section and transversely of said fitting, a frame mounted upon said truck and adapted to be moved transversely thereof into and out of supporting engagement with said detachable wall section, and means for manually actuating said frame.

10 7. In a conveying system, the combination of a pipe connecting fitting, comprising a body member having a wall section detachably connected therewith and adapted to support a wear section for said pipe fitting, a frame movable beneath said detachable wall section and provided with bearing surfaces adapted to engage complementary bearing surfaces of said wall section to support the same, and means for forcing 15 said wall section toward the body member prior to and in the movement of said frame into final supporting position.

8. In a conveying system, the combination of a pipe connecting fitting, comprising a body member having a wall section detachably connected therewith and adapted to support a wear section for said pipe fitting, a truck movable beneath said detachable wall section and transversely of 20 said fitting, a frame mounted to slide transversely upon said truck and adapted to be

moved into and out of supporting engagement with said detachable wall section, and a manually operable screw shaft mounted on said truck and connected with said frame. 45

9. In a conveying system, the combination of a pipe connecting fitting, comprising a body member having a wall section detachably connected therewith and adapted to support a wear section for said pipe fitting, a supporting frame comprising side plates spaced apart and provided with notches adapted to engage lugs on said detachable wall section and with inclined bearing surfaces forming the approach to 50 said notches, and means for moving said supporting frame into and out of supporting engagement with said wall section.

10. In a conveying system, the combination of a pipe connecting fitting, comprising a body member having a wall section detachably connected therewith and adapted to support a wear section for said pipe fitting, a supporting frame comprising side plates spaced apart and provided with 55 notches adapted to engage lugs on said detachable wall section and with inclined bearing surfaces forming the approach to said notches, means for moving said supporting frame into and out of supporting 60 engagement with said wall section, and a truck supporting said frame and movable in a direction transverse thereto.

In testimony that I claim the foregoing as my invention, I affix my signature in the 75 presence of two witnesses, this 2nd day of April, A. D. 1917.

ARTHUR P. STRONG.
